CARBURETOR

Edouard Seignol and Francis Monier, Paris, France, assignors to Societe Auxiliaire pour le Developpement d'Industries Mecaniques S. A. D. I. M., Geneva, Switzerland, a corporation of Switzerland

Application January 11, 1935, Serial No. 1,352
In France January 12, 1934

18 Claims. (Cl. 261—77)

This invention relates to a new arrangement for feeding internal combustion engines.

In known arrangements fuel is fed to carburetors of internal combustion engines either from 5 a gravity tank or a rear low placed tank, fuel from the latter being fed by a raising arrangement or a pump, and the explosive mixture produced by the fuel passes through manifold before arriving at the cylinder inlets.

10 The carburetor according to the present invention lifts the fuel from a low placed tank to a primary carburettng device in which fuel is transformed into a rich mixture, without any exhausting arrangement or pump or other mechanical device, and then feeds the engine directly without requiring a manifold. The atomization of the fuel effected in two stages 15 is perfect.

One float chamber and one fuel feed line only 20 are thus sufficient for feeding multiple secondary carburetor units.

The elimination of the manifold gives a great increase of power, an appreciable economy of fuel and better feeding of the engine.

25 The primary unit may be supplied with hot air from one side of the engine. The secondary unit thus supplied with a hot rich mixture is less subject to the action of cold and allows the use of fuels less volatile than pure petrol.

30 This carburetor is capable of operation whatever the position of the fuel tank may be, whether same is a gravity tank or is disposed at a lower level than the carburetor, the primary unit in the latter case being mounted in such position 35 above the tank that its raising capacity is not exceeded.

The primary carburetor unit may eventually feed only one secondary unit mounted on the usual manifold.

40 Various embodiments of the fuel raising carburetor according to the invention are illustrated by way of example in the attached drawings wherein:

Fig. 1 is a sectional side elevation of one embodiment of fuel raising carburetor according to the invention. It illustrates the whole arrangement of a primary carburetor unit, a double pipe line and two secondary units.

45 Fig. 2 illustrates a valve device mounted on the rich mixture and vacuum tubes connecting one primary carburetor unit to two secondary units.

50 Fig. 3 is a sectional detail view on a larger scale showing the details of the jet and its tube and of the choke tube.

55 Fig. 4 is a vertical sectional view through a

secondary unit, showing the pressure check fitted to the differential vacuum arrangement, also the starting device.

Fig. 5 illustrates the jet output curves.

Fig. 6 is a sectional view illustrating the arrangement for increasing the vacuum in the upper part of the primary unit, in a construction where the throttle valve is disposed at the entrance of the secondary unit.

Fig. 7 illustrates the valve mounted on the differential vacuum arrangement in the construction where the primary carburetor unit feeds only one secondary unit.

Fig. 8 is a vertical sectional view of a part of the secondary carburetor unit, illustrating a form of engine speed control device.

In the following description like reference numerals indicate identical parts.

Referring to Figure 1, the primary carburetor unit connected to the rear tank 1 of a vehicle by a tube 2 comprises a fluid tight casing made in two parts 3 and 3a. The needle valve 4, the lever 5 and the float 6 control the supply of fuel to the float chamber 3 and keep the surface of the fuel at a constant predetermined level.

20 Centrally disposed in the float chamber 3 there is a primary atomizer comprising a chamber 7 communicating with the atmosphere through the openings 8 and the tube 9 which may be heated, a choke tube 10 and a jet 11 communicating with the mass of fuel in the float chamber 3 through the opening 12 and the filter 13.

25 The jet 11 is mounted in member 14 attached to the choke tube, the cone 15 of which is applied to the seating 16 and forms a joint between the central chamber 7 and the float chamber 3. The openings 17 are adapted to allow atmospheric air admitted through pipe 9 to enter the choke tube.

30 The engine suction is communicated to the upper part of the float chamber through the tube 18 and the tube 19 connects the choke tube 10 to the throats of the choke tubes of the secondary units.

35 The primary unit thus constructed is light and fluid tight, and any dislevelling of the vehicle has practically no effect on the action of its jet.

40 This arrangement is not limited to its details and the primary unit may be constructed in any other suitable manner employing equivalents of the parts mentioned, for example the improvement shown in Figure 6.

45 The rich mixture produced by the primary unit is conveyed to the throats 20 of the choke tubes 21 of the secondary carburetors through 50

the openings 22, the annular chambers 23 and the tube 19.

The vacuum obtaining in the choke tubes 21 at the openings 24, the position whereof is determined by experiment, is transmitted to the upper part of the primary units through the chambers 25 and the pipe 18.

Movably mounted in the secondary carburetor units coaxially with the choke tubes 21 there is 10 an air control valve 26 comprising a conical part 27 the sides of which are parallel to the converging portion of the choke tube and a conical part 28, the apex angle whereof is larger than that of the conical part 27.

15 The diameter of the base of the cone 28 is preferably equal to the diameter of the throat 20 of the choke tube 21 multiplied by $\sqrt{2}$. This air control valve is mounted on a tube 29 slidably disposed in a cylinder 32 and subject to the action of a spring 33. The tube 34, which is open at its end 35, transmits the vacuum obtaining in the choke tube into the cylinder 32 under the driving face of the piston 31, whereby the degree 25 of opening of the air inlet valve 26 is controlled.

The calibrated opening 36 brakes the opening movement of the air control valve and the valve 37 nullifies this braking in the closing direction. If the piston actuating the air control valve 26 is 30 inverted as shown in Figure 1, said valve may be moved into its closing position by gravity action or by a counterweight, and the spring 33 may be omitted.

The whole represents an air admission control 35 device, which has the property of accurately proportioning at any degree of its opening a mixture of fuel and air of substantially the most favourable composition.

A throttle valve 38 disposed at the exit of the 40 carburetor and connected to the accelerator by means of a lever 39 controls the speed of the engine.

At the slow running position, the air control valve 26 almost completely closes the entrance 45 of the secondary choke tube 21 and the amount of air entering therein is very small. The vacuum obtaining at the upper part of the primary unit on the top of the fuel level is almost as strong as that obtaining at the tip of the jet and the output 50 of the latter, being almost completely checked by the larger differential vacuum, is very small and amounts to a slow running supply.

If the throttle valve is opened to a certain extent, the vacuum thus formed in the diverging 55 part of the secondary choke tube will be transmitted to the driving face of the piston of the air control valve 26 and thus this valve will open to an extent corresponding to the load of the engine. The same vacuum will also be transmitted to the 60 upper part of the float chamber and the checking action on the jet will be reduced in accordance with the opening of the throttle valve. It follows that the air and fuel supply, controlled by the same vacuum, will be very accurately proportioned.

It is evident that the opening of the air control valve 26 does not follow that of the throttle valve but the value of the vacuum in the diverging part 70 of the secondary choke tube, this opening being reduced with the load of the engine and its speed of rotation.

The control of the slow running feed is obtained by varying, by the means of the needle screw valve 40, the section of the by-pass 41 connecting 75 the vacuum conduit of the secondary carburetor

unit and the carburetor outlet after the throttle valve.

Fig. 2 is a sectional view of the rich mixture or vacuum tubes connecting the primary carburetor unit to multiple secondary carburetors. 5

42 and 43 represent two flat valves mounted in housings 44 and 45 and adapted to be alternately applied to their seatings 46 and 47.

When there is suction in the direction of the arrow f1, the valve 42 is drawn from its seat 10 and becomes seated at 48, allowing the mixture to pass into the channel 49. During this time the pressure in the channel 50 is smaller and the difference of pressure obtaining upon the two faces of the valve causes same to be pressed upon its seating 45, and thus only the secondary unit connected to the channel 49 will be supplied with mixture. 15

When the secondary unit connected to channel 49 has concluded its suction and that connected to the channel 50 begins its suction a reversal takes place, the valve 42 will be applied to its seat 44 by the suction coming from 50 and the valve 43 will move to 51, the secondary unit connected to the channel 50 being supplied with fuel 25 in turn.

Fig. 3 illustrates a primary rich non-explosive mixture forming a device allowing the control of the fuel output.

The choke tube 10 has a cylindrical part 52 of a 30 suitable length for control, disposed between the converging part 53 and diverging part 54 of the choke tube 10. The jet 11 is mounted on a tube 55 disposed centrally in the choke tube and provided with openings 56 disposed substantially at 35 the end of the cylindrical part 52. The tube 55 terminates in the diverging part 54 of the choke tube 10 at such distance from the cylindrical part 52 thereof which may be varied to suit various types of engines. The flatter the jet output curve 40 the shorter said distance will be and vice versa.

The operation of this arrangement is as follows:

During the slow running of the engine the difference of vacuum between the openings 56 45 and the end 57 of the tube 55 increases and a gaseous flow opposed to the flow of the fuel is formed in the tube 55 and checks the output of the openings 56 until the output of these openings becomes insufficient and the fuel rises in the tube 50 55 up to its end 51 for feeding the engine at higher speeds.

The calibration of the openings 56 will therefore permit modifying the output curve of the jet at will and if their total area is larger than 55 the jet area the tube 55 will intervene by its end 57 to control the output of the openings 56 for the whole output curve of the jet.

Fig. 5 illustrates the output curves of the jet.

A is the output curve obtained prior to controlling the differential vacuum.

B is the output curve of the same jet with control of the differential vacuum.

C is the output curve of the jet with the control of the differential vacuum and of the openings 56, 65 so that the end 57 of the tube 55 intervenes in the control of the jet output at all speeds of the engine.

D is the output curve of a jet arrangement wherein the openings 56 are of such area that the 70 output of the jet is checked at low speeds up to the moment when said area becomes insufficient, whereupon the end 57 of the tube 55 directly supplies the fuel.

Fig. 4 is a sectional view of a part of a second- 75

ary carburetor unit and shows details of an improved starting device comprising a tube 58 snugly rotatable in a bore 59 and having openings 60 and 61 which may be brought into register with the 5 channels 62 and 63 respectively.

The tube 58 is secured to a lever 64 which may be operated from the driver's seat.

The operation is as follows:

When starting, the throttle valve 38 being 10 closed, the driver operates the lever 64 connected to the tube 58 and brings the openings 60 and 61 into register with the channels 62 and 63 respectively.

The very high vacuum obtaining on the engine 15 side of the throttle valve 38 is transmitted through the channel 63 into the tube 58 thereby drawing in directly the very rich mixture from chamber 23 of the choke tube.

The calibrated opening 65 disposed at the end 20 of tube 58 allows sufficient air to enter to render the mixture explosive and by dynamic shock produced upon the gaseous column completes the differential automatism of the device.

The starting device may also comprise a 25 throttle valve 66 disposed at the entrance of the secondary carburetor units, as shown in Fig. 1. When said throttle valve is closed the vacuum in the choke tube of the primary unit is considerably increased and as a consequence a difference of 30 vacuum is established which substantially corresponds to full engine speed. The jet will then deliver at its maximum capacity and as only a very small quantity of air is admitted owing to the throttle valve being closed, the resulting very 35 rich mixture will assure instantaneous starting.

Fig. 4 also shows the pressure check 67 adapted to prevent the back flows of the secondary units from becoming effective upon the upper part of the float chamber, so that the jet output should 40 no longer be affected by said back flows.

The valve may be placed at the entrance of the carburetor, thus intensifying the action of the first choke tube and consequently the fuel raising, but this effect requires an arrangement for 45 increasing by a suitable corresponding value the vacuum transmitted by the secondary unit to the upper part of the float chamber of the primary unit.

This arrangement shown in Figure 6 takes the 50 place of the connection of pipe 18 to the secondary carburetor shown in Figure 1, and has a conical bore 68 wherein is centrally disposed a tube 69 extending the vacuum pipe 18 and communicating with the secondary choke tube 21, 55 through the channel 70, the chamber 25 and the apertures 24. Apertures 71 are provided to enable atmospheric air to enter the conical bore 68 and the channel 70. This device increases the 60 vacuum in the tube 69 after the air has reached a certain speed in the conical bore 68, while at 65 small speeds the vacuum in the tube 69 is substantially equal to that in the chamber 25.

During starting a ring 72 closing the air inlet 70 openings 71 puts this device out of action.

Fig. 7 shows the valve 73 which, when the primary unit feeds only one secondary unit, permits the flow from the primary unit to the secondary unit but closes in the opposite direction, thus making all back flow to the primary unit impossible.

Fig. 8 illustrates a form of speed control device in vertical sectional view. The air control valve 26, which is hollow inside, is mounted on the tube 76 which is integral with the piston 31 sliding in the cylinder 32 and subject to the action of spring

33. An air inlet funnel 75, whose free section between its walls and the tube 74 is substantially equal to the exit of the carburetor, is disposed coaxially around the tube 74 under the air control valve. The operation is as follows:

When the air entering the secondary carburetor through the openings 76 and the funnel 75 exceeds a certain value, the underface of the valve 26 reduces the free space between the valve and the funnel, owing to the valve approaching the end of the funnel 75, this reduction being larger in proportion as the speed of the engine has a tendency to increase, thus checking the admission of air into the carburetor, and therewith the speed of the engine.

What we claim is:

1. A fuel raising carburetor for an internal combustion engine comprising, in combination, a primary unit including a fluid tight constant level float chamber having communication with a source of fuel to receive fuel therefrom, a centrally disposed chamber in the primary unit having communication with the atmosphere, a choke tube in said central chamber having a constricted section forming a throat and an air entrance below said throat to receive air from the central chamber, a jet disposed coaxially within said choke tube having its lower end in communication with the float chamber to receive fuel therefrom and its upper discharge end terminating at a level with said throat section, a secondary unit including a choke tube having a constricted section forming a throat and a diverging wall section extending from the throat towards the discharge end of the choke tube, a conduit for conducting fuel from the choke tube of the primary unit to the throat section of the choke tube of the secondary unit, a throttle valve for controlling the discharge of fuel from said secondary choke tube, means for admitting air to the other end of said secondary choke tube, a valve adapted to control the delivery of air into said secondary choke tube from said means, said valve being formed integrally with a piston slideable in a cylinder and provided with a tube extending through the throat section into the diverging wall section so as to transmit the vacuum pressure at this point to the working face of the piston, said valve being responsive to the vacuum acting on the piston to open and gradually retract the entrance of said tube to a position opposite said throat section, a second conduit joining the upper level of the primary unit with said divergent wall section of the secondary unit thereby submitting the upper level of the primary unit to a lesser vacuum than that transmitted by the other connecting conduit to the primary choke tube.

2. A fuel raising carburetor for internal combustion engines comprising, in combination, a primary fuel raising unit including a fluid tight constant level float chamber communicating with a source of fuel to receive fuel therefrom, a centrally disposed chamber in said float chamber having communication with the atmosphere, a choke tube disposed in said central chamber provided with a constricted portion forming a throat and an opening below said throat to admit air from said central chamber, a fuel jet disposed coaxially within said choke tube, said jet having its lower end in communication with said float chamber to receive fuel therefrom and having its upper discharge end terminating at a level with said throat, a plurality of secondary carburetor units each having a choke tube provided with a

constricted portion forming a throat, a throttle valve in the discharge end of each of said secondary choke tubes, a vacuum controlled valve for each of said secondary choke tubes operable 5 to open and close the other end of each of said choke tubes to atmosphere, said throat portions of each of said secondary choke tubes provided with a fuel inlet, a conduit for delivering fuel from said primary choke tube and provided with 10 branch sections for delivering fuel individually to each of said fuel inlets, a second conduit extending from the upper level of the primary unit and provided with branch sections each communicating with one of said secondary choke tubes, said 15 branched sections each provided with a valve member responsive to the differential pressure existing in said conduits to open and close each of the branch sections to their respective secondary unit.

20 3. A fuel raising carburetor for internal combustion engines comprising, in combination, a primary fuel raising unit, a plurality of secondary carburetor units, a fuel delivery system connecting said primary unit with said secondary units 25 and comprising a conduit extending from the primary unit and branched to deliver fuel individually to each secondary unit, an air conduit likewise connecting said primary unit with said secondary units and branched similarly to provide 30 individually communication with each secondary unit, each of said branch conduits being controlled by a valve responsive to the differential pressure existing in said conduits to open and close communication between the primary unit 35 and each of said secondary units.

4. A fuel raising carburetor for internal combustion engines comprising, in combination, a primary fuel raising unit, a plurality of secondary carburetor units, a conduit extending from said 40 primary unit and provided with branched sections each leading to one of said secondary units, a valve longitudinally movable in each branch section and operable in one position to close the branch section and in another to open the branch 45 section, each of said valves being responsive to the differential pressure existing in said conduit system on either side thereof to shift to closing or opening position.

5. A fuel delivery system for an internal combustion engine comprising, in combination, a primary fuel raising unit having a choke tube provided with a constricted portion forming a throat, a secondary carburetor unit likewise having a choke tube provided with a constricted 55 portion forming a throat, a fuel jet mounted coaxially within said primary choke tube, said fuel jet communicating at its lower end with the fuel content of said primary unit and extending upwardly within said choke tube at least 60 as far as said throat, means for admitting air into said primary choke tube, and means for delivering fuel from the primary choke tube to the throat of the secondary choke tube.

6. A carburetor device comprising, in combination, a primary fuel raising unit, a secondary carburetor unit, said primary unit having a chamber for receiving fuel and a float controlled valve for controlling the admission of fuel to the chamber, a choke tube in said chamber having a 65 constricted portion forming a Venturi throat and diverging wall sections on either side of the throat, means for delivering air to the choke tube below the Venturi throat, a tube mounted coaxially within said choke tube having communication at its lower end with said chamber 70

to receive fuel therefrom, said tube extending upwardly within said choke tube and having its discharge end terminating substantially opposite said Venturi throat section, said secondary carburetor unit likewise provided with a choke tube having a Venturi throat, and a conduit connecting the two choke tubes and operable when sub-atmospheric air pressure exists therein to entrain fuel from the primary choke tube to the secondary choke tube. 10

7. A carburetor device comprising, in combination, a primary fuel raising unit a secondary carburetor unit, said primary unit having a chamber for receiving fuel and a float controlled valve for controlling the admission of fuel to the chamber, a choke tube in said chamber having a constricted portion forming a Venturi throat and diverging wall sections on either side of the throat, means for delivering air to the choke tube below the Venturi throat, a tube mounted coaxially within said choke tube and having communication at its lower end with said chamber to receive fuel therefrom, said tube extending upwardly through the Venturi throat and terminating in the diverging wall section thereabove, said tube provided with an opening opposite the Venturi throat where the maximum vacuum is encountered, said secondary carburetor unit likewise provided with a choke tube having a Venturi throat, and a conduit connecting the two choke tubes and operable when sub-atmospheric air pressure exists therein to entrain fuel from the primary choke tube to the secondary choke tube. 20

8. A carburetor device for an internal combustion engine comprising, in combination, an air passage having a constricted section forming a Venturi throat, a throttle valve in said passage controlling the discharge therefrom, means for delivering fuel into said air passage at the level of said throat, a by-pass for delivering a rich mixture of fuel to said passage beyond the effective position of said throttle valve including a rotatable tube extending lengthwise of said passage, a fuel conduit communicating with said fuel delivery means and said rotatable tube and adapted to deliver a rich mixture of fuel from the former to the latter, a fuel conduit extending from said tube to the air passage on the side of said throttle valve remote from said throat, said tube having ports adapted in one position of its rotation to communicate with said fuel conduits, means for rotating said tube, and means for introducing air into said tube in a direction opposing the flow of fuel by-passed therethrough. 30

9. A starter control device for a carburetor of an internal combustion engine having a fuel passage and a throttle valve controlling the discharge of fuel through said passage comprising a tube positioned for rotatable movement adjacent said passage and provided with ports adapted in one position of the tube's rotation to communicate with the passage on either side of said throttle valve for the purpose of by-passing fuel therearound, said tube having an air inlet arranged to direct air into said tube in a direction opposing the flow of fuel by-passed through the tube. 40

10. A fuel raising carburetor device for an internal combustion engine comprising, in combination, a chamber having a fuel inlet for receiving fuel and means for controlling the admission of fuel to maintain a constant level of fuel therein, means for raising fuel above the 75

level of the fuel in said chamber comprising a series of tubes mounted coaxially with respect to one another and in spaced relationship to one another, the outer tube forming an air tube adapted to deliver air below the level of the fuel in the chamber, a choke tube within said outer air tube having a constricted portion forming a Venturi throat passage and communicating with the outer air tube below the Venturi throat for receiving air therefrom, and a third tube within said choke tube communicating with the fuel in the chamber at its lower end and extending upwardly in the choke tube at least as far as the Venturi throat section, said third tube adapted when sub-atmospheric pressure exists in said choke tube to entrain fuel upwardly therethrough and discharge the same into the choke tube where it mixes with the air therein.

11. A fuel raising carburetor device for internal combustion engines comprising, in combination, a chamber having a fuel inlet for receiving fuel and a float for controlling the admission of fuel through the inlet, said float provided with a hole extending therethrough, an air tube positioned within the hole in said float and communicating at its upper end with the atmosphere, a choke tube of less diameter than said air tube positioned coaxially within the latter in spaced relation to the said walls thereof, said choke tube having a constricted section forming a Venturi throat and an opening below the Venturi throat to admit air from said air tube, and a fuel pipe positioned coaxially within said choke tube communicating with the fuel in said chamber at its lower end and extending upwardly within the choke tube at least as far as said Venturi throat section.

12. A fuel raising carburetor device for an internal combustion engine comprising, in combination, a fuel chamber having a fuel inlet for receiving fuel and means for maintaining a constant level of fuel therein, a choke tube in said chamber extending below the level of the fuel and provided with a constricted section forming a Venturi throat, means for delivering air to said choke tube below said Venturi throat section, a tube mounted co-axially within said choke tube having communication with the fuel content of said chamber at its lower end and having its upper discharge end terminating within said choke tube at a point above said Venturi throat section, said last mentioned tube provided with an opening opposite the Venturi throat section, said second tube adapted when sub-atmospheric pressure exists in said choke tube to entrain fuel upwardly therethrough and mix the same with the air in the choke tube as it is discharged therefrom.

13. A fuel delivery system for an internal combustion engine comprising, in combination, a constant level primary carburetor unit and a throttle valve controlled secondary carburetor unit, a fuel conduit connecting said units together and adapted when sub-atmospheric pressure exists therein to conduct fuel from the primary unit to the secondary unit, said conduit having one section thereof in the form of a tube of less diameter than the conduit and extending longitudinally within the conduit for a short distance in spaced relation to the wall of the conduit, means for admitting air through the conduit and into the space surrounding said tube, means for regulating the amount of air so admitted, and means for causing the admitted air to pass the discharge end of said tube under relatively high

velocity so as to increase the vacuum at this point.

14. A carburetor starter device for an internal combustion engine comprising, in combination, a fuel passage, a throttle valve in said passage controlling the flow of fuel therethrough, a fuel conduit for by-passing fuel around said valve having communication with said passage on one side of said valve to receive fuel therefrom and having communication with said passage on the other side of said valve to discharge fuel thereinto, said fuel conduit having a constantly opened calibrated air port arranged to admit air into the conduit in a direction opposing the flow of fuel by-passed therethrough and means under manual control for simultaneously opening and closing both of said communications between said conduit and said passage.

15. A fuel raising carburetor for internal combustion engines comprising, in combination, a primary carburetor unit including a constant level fuel chamber communicating with a source of fuel to receive fuel therefrom, an air intake into said chamber, a choke tube disposed in said air intake, said choke tube provided with a constricted portion forming a throat and an opening below said throat to admit air from said air intake, a fuel jet disposed coaxially within said choke tube, said jet having its lower end in communication with said float chamber to receive fuel therefrom and its upper discharge end terminating within the length of said choke tube, a secondary carburetor unit including a choke tube provided with a constricted portion forming a throat, means for admitting air to one end of said secondary choke tube, a vacuum controlled valve for controlling said last means, a throttle valve for controlling the flow of fuel through said secondary choke tube, and means establishing communication between said primary unit and said secondary unit including a conduit for delivering fuel from the choke tube of said primary unit to the choke tube of said secondary unit, and an air conduit connecting the upper interior level of said primary unit with the choke tube of said secondary unit and provided with a valve responsive to differential air pressures in the conduit to open and close the same in accordance therewith.

16. A fuel raising carburetor for internal combustion engines comprising, in combination, a primary carburetor unit, a secondary carburetor, a fuel delivery conduit extending from said primary unit to said secondary unit, an air conduit likewise connecting said primary unit with said secondary unit, and a valve in said air conduit responsive to differential air pressures existing therein to open and close communication between said primary unit and said secondary unit.

17. A fuel raising carburetor for internal combustion engines comprising, in combination, a primary carburetor unit, a secondary carburetor unit, a conduit extending between said primary unit and said secondary unit, a valve member longitudinally movable in said conduit and operable in one position to close said conduit and in another position to open said conduit, said valve being responsive to differential pressures existing in said conduit to move to either an open or closed position.

18. A fuel delivery apparatus for an internal combustion engine having a closed substantially constant level fuel chamber and mixing chamber to which fuel in said constant level chamber is delivered, an air conduit communicating

between said mixing chamber and the interior of said constant level chamber above the level of the fuel therein, a valve element floatingly mounted in said conduit and operable in one position to close the conduit and in another position to open the conduit, said valve being

sensitive to differential air pressures existing in said conduit to assume either the open or closed position in accordance therewith.
